COMPRESSOR

Vadim S. Makaroff, New York, N. Y., and Alexis E. Jackson, Norwalk, Conn.

Application November 22, 1952, Serial No. 321,965

5 Claims. (Cl. 230—147)

1 The invention relates to rotary compressors of the type shown in U. S. Patent No. 1,664,733 to Braun and is a continuation-in-part of our U. S. application, Serial No. 304,512, filed August 15, 1952.

The prior patent relates to a compressor having a cylindrical chamber in which an eccentrically mounted cylindrical piston gyrates. The piston is provided with a tail blade which reciprocates within an oscillatory valve block to control the discharge of the compressed gas.

The prior patent discloses a structure which is mechanically simple but is not thermo-dynamically efficient. Among the reasons for such inefficiency are the opening and closing of the port in the valve block at the wrong times and the failure to recognize the fact that different generated pressures require different relationships between the tail blade on the one hand, and the center of the piston or of the valve block on the other hand.

Among the objects of the present invention are to overcome the aforesaid disadvantages.

In the drawings:

Fig. 1 is a diagram of a compressor, illustrating the position of the piston at the opening point of the discharge valve port, of an embodiment of the invention in which the tail blade is mounted on a radius of the piston, and in which the slot for the tail blade passes through the valve center;

Fig. 2 is a diagram of the same compressor as Fig. 1, illustrating the position of the piston at the closing point of the discharge valve port;

Fig. 3 is a diagram of another embodiment of a compressor, illustrating the position of the piston at the opening point of the discharge valve port, with the tail blade in non-radial position with respect to a piston radius;

Fig. 4 is a diagram of the same compressor as Fig. 3, illustrating the position of the piston at the closing point of the discharge valve port;

Fig. 5 is a diagram of another form of compressor, illustrating the position of the piston at the opening point of the discharge valve port, in which the tail blade is mounted on a radius of the piston, and in which the slot for the tail blade is offset from the center of the valve member;

Fig. 6 is a transverse vertical section through a compressor, according to the invention, taken on the line 6—6 of Fig. 7 and illustrating the compressor structure; and

Fig. 7 is a transverse vertical section of a compressor, according to the invention, taken on the line 7—7 of Fig. 6, and showing the discharge

2 valve port partly open. In this figure the offset of the tail blade is the same as in Figs. 3 and 4.

Fig. 8 is a diagram of still another form of compressor, illustrating the position of the piston at the opening point of the discharge valve port, in which the tail blade is in non-radial position with respect to a piston radius, and in which the slot for the tail blade is offset from the center of the valve member.

10 In the following description and in the claims, various details will be identified by specific names for convenience, but they are intended to be as generic in their application as the art will permit.

15 Like reference characters denote like parts in the several figures of the drawings.

20 In the drawings accompanying and forming part of this specification, certain specific disclosure of the invention is made for purposes of explanation, but it will be understood that the details may be modified in various respects without departure from the broad aspect of the invention.

25 Referring to the drawings, and more particularly to Figs. 6 and 7, the compressor structure will first be described. The compressor comprises a casing 10 having a main cylindrical chamber or cylinder 11, a cylindrical valve housing 12 parallel thereto, the housing and chamber intersecting to form an arcuate space through which the tail blade 13 of the piston passes. An eccentrically gyrated cylindrical piston 14 is mounted in the main chamber and an oscillatory valve block or member 15 is mounted in the valve housing 12. The piston 14 has the offset, integral tail blade 13 whose center line is non-radial with respect to the center of the piston 14. The valve block 15 has a slot in which the tail blade 13 reciprocates.

30 The casing 10 has a low pressure inlet duct 16 and a high pressure outlet duct 17. The valve block 15 has a discharge port 18 adapted to connect the high pressure duct 17 and the main chamber 11 at times, and to disconnect the high pressure duct and the main chamber at other times. The casing has recess 21 to provide clearance for tail blade 13. It will be noted that the intersection of the valve housing 12 and main cylindrical chamber forms a lip 22 adjacent the port 18. It will be seen from discussion below that this lip 22 is a critical point for completion of closing of the valve port 18.

35 The casing 10 comprises end plates 19 with a body member 20 clamped in between by a series of bolts. The end plates 19 have recesses 24 for ring-like hubs 23 which connect the two halves of the valve member 15 together. The

valve member bears on, and is journaled in, the housing or socket 12. The sides of the tail blade 13 slidably engage with the end plates 19.

The end plates 19 have bearings 25 journaling a main shaft 26 which has crank arms 27 between which extends a crank pin 28. Around the crank pin 28 is a split bearing 29 having longitudinal holes 30 therein. The split bearing 29 is shorter than the length of the piston 14, thus providing spaces 32 communicating with the holes for the circulation of oil. The piston 14 slidably engages the end plates 19. The end plates have clearance spaces 31 to permit rotation of the crank arms 27.

An oil circulating system is provided for lubricating and sealing the parts. The discharge duct 17 connects with a storage tank (not shown) for the compressed gas as indicated in the prior application. The bottom of the storage tank constitutes an oil reservoir. The main oil feed pipe 33 feeds oil from the bottom of the oil reservoir to the space 32 inside of the piston 14. The main bearings 25 have annular oil recesses to which pipes 36 are connected, these pipes leading to a common pipe 37 which leads to the supply pipe 38 which connects with the intake duct.

It will be understood that the crank shaft 26 is driven by any suitable means through a suitable coupling 39. This causes the piston 14 to gyrate eccentrically around the main cylinder 11 clockwise as indicated by the arrows. Gas is drawn in through the intake duct 16 and discharged through the outlet duct 17.

The lubrication system works as follows. Oil 35 under pressure from the reservoir is forced through pipe 33, in the direction of the arrow, into the spaces 32, thence into the main cylinder 11, into the crank bearing and piston bearing; 30 thence out through the two main bearings 25, and thence into the bearing drain pipes 36 and through common pipe 37 into the inlet pipe 38. The tail blade 13 is provided with oil channels 39 which conduct oil to the valve block 15 which oil drains back into the main cylinder.

It will be noted that the tail blade 13 in Figs. 6 and 7 is offset with respect to the piston center, that is, it is non-radial; and that the center line of the tail blade passes through the center of rotation of the valve block 15. This particular relationship of piston, tail blade and valve is but one example of a variety of relationships. We have found that, for best efficiency at any given speed of rotation, this relationship depends upon the value of the pressure to which it is desired to compress the gas.

Examples of other relationships for other pressures are shown in Figs. 1 to 5 and 8. In Figs. 1 and 2, the center line of the tail coincides with the piston radius and passes through the center of the valve member. In Figs. 3 and 4, the relationship is substantially the same as illustrated in Figs. 6 and 7. In Fig. 5, the center line of the tail blade is coincident with a piston radius and passes through the valve member at a point offset from the center of rotation. It will be understood that the tail blade may have other angles with respect to the piston, and the slot for the tail blade may be offset other distances from the valve axis. Also, as illustrated in Fig. 8, arrangements of both offset tail blade and offset slot in the same compressor may be provided according to our invention.

It will be understood that the bearing between the gyrating piston 14 and the crank pin on 75

which it is journaled is such that there is no actual contact between the piston 14 and the cylinder 11. The center of the piston describes a circular path (as indicated by 40 in Fig. 1, for example), and the surface of the piston maintains close sealing relationship to the cylindrical walls of the chamber, the sealing being accomplished by a film of oil or other liquid.

Nevertheless, for convenience, the point on the piston at which sealing takes place will be sometimes referred to as the "contact point" or "sealing point;" this is the point (42 for example in Fig. 1) through which the line 43 passes, which line also passes through the center 44 of the cylindrical chamber and the center 48 of the piston. This contact point is not always the same point on the piston, but changes with the position of the piston, as will be understood. In the description when the position of the piston is referred to, it usually refers to the position of the contact point.

The importance of always having proper relationship between position, tail blade and valve will be more apparent from the following discussion, particularly with respect to Figs. 1-5.

As stated, the piston 14 gyrates in a clockwise direction, as indicated by the arrow. Dead center will be assumed to be position the piston takes when its center is located on a vertical line 41 passing through the center of the valve cylinder and through the center of the main chamber. All angular relationships of the piston, as it sweeps around in its cylinder, will be referred to with respect to upper dead center which is designated as zero degrees. Lower dead center is indicated as 180°.

As stated, as the piston 14 gyrates around in its cylinder, it draws gas in behind it through intake opening 16 and forces gas ahead of it out through discharge opening 17. It will be noted that the gas begins to compress as soon as the piston 14 passes the inlet port. This gas is compressed during the angular rotation of the piston from the inlet port to the valve-opening point (42 in Fig. 1). When the piston 14 reaches the opening point, the valve 15 opens and compressed air is forced into the discharge duct 17 until the piston 14 reaches the closing point (45 in Fig. 2), at which point the valve 15 closes. The valve 15 remains closed all the while the piston describes the angle from the closing point 45 around to the opening point again.

It will be noted that the closing point 45 is exactly at the lip 22 formed by the intersection of the valve housing and the main cylinder. This relationship is important. It will be noted, particularly from Fig. 2, that if the valve does not close until after the contact point reaches the near edge or lip of the arcuate gap, high pressure generated in the high pressure discharge duct 17 can escape back into the low pressure space behind the piston 14. On the other hand, if the valve 15 closes before the contact point reaches said lip, gases will be trapped in space ahead of the piston 14 between the contact point and the tail blade 13, with no place for these gases to flow.

As stated, actual tests show that the angular position of the contact point corresponding to opening position of the valve, must vary with different generated pressures for best efficiency; and the contact point corresponding to closing position of the valve must always be at the lip 22, regardless of generated pressure.

In building a compressor for a given pressure,

the angular position of the contact point for valve opening, i. e. the valve-opening point (42 in Fig. 1, for example) must first be determined. This may be determined empirically, or by test. Specific examples of the correct angles for the valve-opening point for different pressures will be given below.

A straight line (46 in Fig. 1) is then drawn between the valve-opening point 42 and the valve-closing point or lip 22. If it is desired to have the slot for the tail blade 13 pass through the valve center, a parallel line (47 in Fig. 1) is drawn through the center of the valve 15. It will be noted that, in Figs. 1 and 2, this line 47 passes through the center of the piston 14, making the tail blade 13 radial with respect to the piston; this is pure coincidence, as this condition occurs only for the special case where the valve-opening position is at about 203°. With the piston in valve-opening position and the radial tail blade passing through the valve center, the valve port 18 will then be cut to such a length as to time valve opening exactly at this point.

The manner of determining the length of valve port 18 for other generated pressures should be clear from the above explanation. In Figs. 3 and 4, the valve-closing point will be at the lip 22, as explained above. The valve-opening point 42 is located at about 230°. The line 46 is drawn between these two points. A parallel line 47 is drawn through the valve axis. This parallel line defines the position of the tail blade 13, which is nonradial with respect to the piston. The valve port 18 is cut to just open the valve at this point.

In Fig. 5, the valve-opening point 42 is located at about 210°. A line 46 is drawn through point 42 and lip 22. A parallel line 47 is drawn through the piston center, which line passes through the valve member 15 at a point offset from the valve axis. This line 47 determines the position of the slot through which the tail blade passes. The valve port is then cut to just open the valve at this point.

In Fig. 8, the valve opening point 42 is located at about 220°. A line 46 is drawn through point 42 and lip 22. A line 47 parallel to 46 is drawn, as shown. This line 47 passes neither through the piston center nor the center of the valve member. This line 47 determines the position of the tail blade and also the position of the slot through which the tail blade passes. The valve port 18 is then cut to just begin to open the valve at this point.

Ordinarily, variation for compressed gas pressure will be accomplished by properly positioning the tail blade 13 as in Figs. 1, 2, 3, 4, 6 and 7, instead of using the treatment illustrated in Fig. 5 or Fig. 8.

It will be noted that, in any of the above constructions, the valve-opening and valve-closing points of the piston bear a definite fixed relationship to each other; this can be better understood by considering a theoretical movement of the piston from one position to the other. That is to say, assuming the piston to be disconnected from its crank pin, and assuming the valve block to occupy a fixed position with the valve just ready to open or close, the piston may be moved between its valve-opening and valve-closing points by simply moving the piston tail blade lengthwise in its slot.

As stated above, there is only one position of the piston at which the valve should close, re-

gardless of generated pressure. This is when the contact point is at the lip 22. There are many positions at which the valve should open, depending upon the particular pressure for which the compressor is designed. In our tests we found that at 1740 R. P. M. when the valve-opening position is at about 180°, the compressor is efficient up to generated pressures of about 50 pounds gauge; if the valve opens at 215°, the best efficiency is obtained at about 150 pounds gauge generated pressure.

It will be understood that liquids other than oil may be used for sealing and lubricating. Also, the compressor may be used as a vacuum pump; and the compressor may be run as a motor, without change, by applying motive pressure to the discharge duct. Hence, in the claims the use of the term "compressor" and other terms to describe the compressing function are intended to cover the use of the present invention as a vacuum pump and as a motor, as well as a compressor.

The operation of the compressor is not dependent upon spring pressed check valves which, by their very nature, are not sufficiently fast acting for all purposes, at high speeds. This enables the present compressor to be run at higher speeds, tests indicating up to 2000 and even 3600 R. P. M.

While certain novel features of the invention have been disclosed herein, and are pointed out in the annexed claims, it will be understood that various omissions, substitutions and changes may be made by those skilled in the art without departing from the spirit of the invention.

What is claimed is:

1. A rotary compressor comprising a casing having a main cylindrical chamber, a valve chamber intersecting said main chamber and forming a pair of lips therewith, an eccentrically gyrating piston in said main chamber, an oscillatory valve member in said valve chamber, a discharge port in the valve member adjacent one of the lips, a tail blade on said piston and integral therewith, said valve member having a slot in which said tail blade reciprocates, said casing having a low pressure inlet duct and a high pressure outlet duct, said inlet duct communicating with said main chamber, said discharge port being adapted to connect said high pressure duct and said main chamber at times and to disconnect said high pressure duct and said main chamber at other times, as the valve member oscillates, characterized in this that the center line of the tail blade has such a position with respect to the center of the piston and with respect to the center of the valve member that, at any selected contact point of the piston with the wall of the main chamber on the compression stroke of the piston, predetermined for the beginning of the opening of the outlet duct, the center line of the tail blade is parallel to a line drawn from said contact point to the tip of the lip adjacent the discharge port whereby the closing of the outlet duct is completed when the point of contact of the gyrating piston with the wall of the main chamber reaches the said tip of the lip adjacent the discharge port.

2. The rotary compressor according to claim 1 in which the center line of the tail blade is offset from the center of the piston.

3. The rotary compressor according to claim 1 in which the center line of the slot is offset from the center of the valve member.

4. The rotary compressor according to claim

1. in which the center line of the tail blade is offset from the center of the piston, and the center line of the slot is offset from the center of the valve member.

5. The rotary compressor according to claim 1 in which said inlet duct communicates with the said main chamber at a point spaced from the valve member and from the tail blade.

VADIM S. MAKAROFF.
ALEXIS E. JACKSON.
